Primary Examiner — Cathron Brooks*Assistant Examiner* — Sydney R Buffalow(74) Attorney, Agent, or Firm — Leanne Taveggia Farrell; Westman, Champlin & Koehler, P.A.(57) CLAIM

The ornamental design for a coat rack, as shown and described.

DESCRIPTION

FIG. 1 is a perspective view of a coat rack showing our new design;

FIG. 2 is a front view thereof, the back, the right side and the left side being identical;

FIG. 3 is a top view thereof; and,

FIG. 4 is a bottom view thereof.

The broken lines shown in the drawings are included for purposes of illustrating portions of the coat rack and form no part of the claimed design.
